UNITED STATES PATENT OFFICE.

ETHBERT CLAYTON RICHMOND, OF TACOMA, WASHINGTON.

SOUVENIR.

No. 926,440.

Specification of Letters Patent.

Patented June 29, 1909.

Application filed March 6, 1909. Serial No. 481,589.

To all whom it may concern:

Be it known that I, ETHBERT C. RICHMOND, a citizen of the United States, and a resident of Tacoma, in the county of Pierce and State of Washington, have invented a new and Improved Souvenir, of which the following is a full, clear, and exact description.

The invention is an improvement in souvenirs, the same consisting of a body having the 10 opposite side faces inclining inwardly from each end toward the transverse center and having the edges scored to simulate a package of shingles, the representation being further perfected by placing cross-bars at opposite sides of the contracted central portion of 15 the body, joining the adjacent ends of the bars by metallic straps and nailing the overlapping ends of the straps and bars to the body.

Reference is to be had to the accompanying drawings forming a part of this specification, in which similar characters of reference indicate corresponding parts in all the views.

Figure 1 is a perspective view of one form of the souvenir; Figs. 2 and 3 are perspective 25 views respectively of an outer and inner stave of the body shown in Fig. 1; and Fig. 4 is a perspective view of another form of the souvenir.

In the construction of the souvenir, as 30 shown in Figs. 1 and 4, a rectangular body 5 has the opposite side faces inclining inwardly from each end toward the transverse center, making the center of the body of contracted thickness. In both forms of the invention, 35 the inclined faces of the body are longitudinally scored, as indicated at 6, and vertically scored at the ends, as indicated at 7, with the vertical scoring breaking joint and imparting to the body the appearance of a 40 package of shingles. This appearance is rendered more realistic by a tie of cross-bars 8 at opposite sides of the body on the contracted central portion thereof and connecting the adjacent ends of the bars by straps 45 9, the straps having overlapping end por-

tions which are nailed to the bars, the nails passing into the body.

In the construction shown in Fig. 4, in which the body is of a single piece, the effect of a shingle package is made complete by 50 forming shoulders 10 crosswise of the body on the opposite inclined faces, and scoring the side edges and ends of the body in planes at right-angles to the vertical scoring 7, the scoring being of a nature at the side edges of 55 the body to represent the inner ends of the shingles overlapping, as in the case of a full size package of shingles.

The construction shown in Fig. 1 differs from that of Fig. 4 only in making the body 60 up of a number of separate staves 11, as shown in Figs. 2 and 3, the joints between these several staves serving the purpose of the scorings intersecting the scoring mark 7, as when the body is of a single piece. 65

Having thus described my invention, I claim as new and desire to secure by Letters Patent:

1. A souvenir comprising a body having the opposite side faces inclining inwardly 70 from each end toward the transverse center and having the edges scored to simulate a package of shingles.

2. A souvenir comprising a body having the opposite side faces inclining inwardly 75 from each end toward the transverse center and having the edges scored to simulate a package of shingles, and cross-bars extending across the contracted center of the body and having connecting straps nailed thereto and 80 to the body to represent a tie for the package.

In testimony whereof I have signed my name to this specification in the presence of two subscribing witnesses.

ETHBERT CLAYTON RICHMOND.

Witnesses:

D. W. MOSER,
E. L. BURNHAM.
